UNITED STATES PATENT OFFICE.

WILLIAM H. BEHRENS, OF NEWARK, NEW JERSEY, ASSIGNOR OF ONE-HALF TO CHARLES M. THEBERATH, OF SAME PLACE.

MACHINE FOR HARDENING AND SIZING HAT-BODIES.

SPECIFICATION forming part of Letters Patent No. 287,752, dated October 30, 1883.

Application filed April 6, 1883. (No model.)

To all whom it may concern:

Be it known that I, WILLIAM H. BEHRENS, a citizen of the United States, residing at Newark, in the county of Essex and State of New Jersey, have invented certain new and useful Improvements in Machines for Hardening and Sizing Hat-Bodies; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in machines for hardening and sizing hat-bodies, and has for its object greater simplicity of construction and efficiency of action, whereby the capability of such machines is greatly increased.

The invention consists of such arrangements and combination of parts as will be herein-after set forth, and finally embodied in the claims.

In the drawings, in which similar letters of reference indicate like parts in each of the several figures, Figure 1 is a vertical section of a machine embodying my improvements, taken through the center. Fig. 2 is a side elevation of the same. Fig. 3 is a front elevation of the same.

The operation and construction of my invention are substantially as follows:

a is the frame of the machine, constructed as shown in the drawings, having preferably a triangular form, as indicated, for the purposes hereinafter specified.

b is a wheel secured to the shaft *b'*, which passes midway through the machine, and has secured thereto the slotted bar *c*, which is connected with the slotted bar *e* by the adjustable link *d*, the said bar *e* being secured to the shaft *f*, which may run across the top of the machine, having the wheel *f* attached to the said shaft *f'*, preferably on the opposite side of the machine.

The power being applied to the wheel *f*, the rotary motion here produced is converted into a reciprocating or rocking motion in the bar *c*, and consequently in the shaft *b'* and wheel *b*. The extent of the rocking motion

can be regulated by means of the link *d* being adjustable in the slots in the bars *e* and *c*, as is evident by reference to Fig. 2. The bars *c* and *e* may be extended and weighted, if desirable, so as to balance the parts and give steadiness of motion.

Extending partly around the wheel *b*, and fastened thereto by a pin or bolt, as at *b'*, Fig. 1, is the cord or belt *g*, which is attached to the sliding or working frames *h*, said working frames moving on rollers in the slanting or converging slots or ways in the frame *a*, as shown in Figs. 1 and 2. The extent of the inclination of the slots or ways in the frame may be varied to produce the best working results.

At the top of the machine, secured to the frame-work thereof, are one or more pulleys, placed as may be desirable, over which run the cords or belts *k*, Fig. 1, which are fastened to the working-frames *h*, thus connecting the working-frame on one side of the wheel *b* with the working-frame on the other side of said wheel, as shown in Fig. 1. The rocking motion of the wheel *b* causes the working-frame *h* on one side to descend, while at the same time the working-frame on the other side, being connected with the descending frame by the cord *k*, ascends, and so on, the working-frames ascending and descending as long as the rocking motion of the wheel *b* is continued.

Attached to the frame-work of the machine by the slotted pieces *n* are the frames *l*, the said slotted pieces being bolted to the frame *l*, and the slot working over a pin on the frame of the machine, the pin having a thumb-screw thereon, so as to secure the piece *n* in place. Rollers may engage with the piece *n*, so as to facilitate its movement. The slotted piece may be reversed, if desirable, having the slot and pin on the frame *l*.

Within the frames *l*, and hinged or secured thereto, are the frames *m*, as shown in Figs. 1 and 2. The said frames *m* are provided with a suitable catch, and may be called "stationary frames," in distinction from the working-frames *h*.

The frames *l* may be attached to the frame of the machine by a pin running through an eyebolt at the bottom of the frame *l* into the frame of machine, having a spring around said pin, as shown in the drawings, Figs. 1

and 2, thus serving as a hinge. An ordinary hinge may be used, if desired.

The working-frames *h* and stationary frames *m* are provided with an elastic bed, *o*, Figs. 1, 5 2, and 3, made of reeds or strips, either flat, round, or angular, arranged in the said frames horizontally, vertically, or obliquely, as may be necessary or desirable. A solid elastic bed may also be used, made of cloth, canvas, 10 thin board, or other suitable material. The reeds, strips, or other forms used in the elastic bed may be made of wood, rubber, gutta-percha, or steel; or either of these materials may be covered with rubber, as may be most 15 suitable to the requirements of the work. Attached by one end to the upper part of the stationary frame *m*, or to one of the reeds therein, and by the other end to an elastic strip or reed arranged above the working- 20 frame *h*, and hanging down between the said working and stationary frames, is a strip, *p*, Figs. 1 and 2, made of cloth, canvas, or other suitable material, forming a sack, into which are placed the hat-bodies to be hardened or 25 sized. The said strips *p*, being secured at their ends to elastic reeds, sag in the middle, thus preventing the hat-bodies from slipping out of the sack.

The machine operates substantially as follows: 30 The hat-rolls—as many as the machine will contain—being placed within the sack between the working and stationary frames, the working-frame, moving up and down, tumbles or rolls the hat-bodies between the elastic beds, thus producing the result desired. The stationary frame *m* and the frame *l*, to which it is hinged or secured, may be moved nearer to or farther from the working-frame and still kept parallel therewith by means of the slotted attachments 35 *n*, thus allowing a greater or less number of hat-bodies to be placed within the sack *p*. The bodies, being sufficiently rolled, may be removed by opening the stationary frame *m*, as shown in Figs. 1, 2, and 3, and the rolls will 40 fall into the hands of the operator. Adjacent to the machine may be placed a tank for the sizing-liquid, which can be pumped therefrom upon the rolls in the machine. The back of the working-frame may be boarded or covered, 45 as at *r*, Fig. 1, so as to prevent the liquid from dripping upon the machinery. A trough leading into the tank may be placed below, so as to catch the liquid and conduct it back 50 into the tank.

55 The form and arrangement of the parts of the machine may be changed without departing from the spirit of my invention—viz., the working-frames may move vertically or horizontally, as well as obliquely, the stationary frames conforming thereto, if it should be so desired.

Having thus described my invention, what I claim as new, and wish to secure by Letters Patent, is—

1. The combination, with the frame *a* of a 65 hat hardening and sizing machine, of a wheel, (as *b*.) shaft *b'*, slotted bar (as *c*) having an extended portion, (as *c'*.) adjustable link, (as *d*.) slotted bar (as *e*) having an extended portion, (as *e'*.) a shaft, *f'*, and a wheel, (as *f*.) 70 all substantially as and for the purposes herein set forth.

2. The combination, in a hat hardening and sizing machine, of mechanism for converting a 75 rotary motion into a reciprocating or rocking motion with a working frame or frames (as *h*) having an elastic bed, (as *o*.) and connected by belts or cords, (as *k*.) all substantially as and for the purposes herein set forth.

3. In a hat hardening and sizing machine, 80 the combination, with a rocking wheel (as *b*) of working-frames (as *h*) connected by cords or belts, (as *k*.) and stationary frames, (as *m*.) all the said frames being provided with an elastic bed, (as *o*.) all substantially as set forth. 85

4. The combination, in a hat hardening and sizing machine, of a working-frame, (as *h*.) and a stationary frame, (as *m*.) said frames being provided with an elastic bed, (as *o*.) all substantially as set forth. 90

5. The combination, in a hat hardening and sizing machine, of a working-frame (as *h*) with a stationary frame, (as *m*.) said frames being provided with elastic beds, (as *o*.) and having between them a sack or receptacle (as *p*) for holding the hat-rolls, one end or side of said sack being attached to the working-frame, and the other end or side to the stationary frame, all substantially as and for the purposes set forth. 95

6. In a hat hardening and sizing machine, the combination, with a working-frame (as *h*) having an elastic bed, (as *o*.) of a stationary frame, (as *m*.) also provided with an elastic bed, (as *o*.) and secured or hinged to or 105 within an adjustable frame, (as *l*.) all substantially as set forth.

7. In combination, the wheel *f*, shaft *f'*, slotted bar, (as *c*.) link, (as *d*.) slotted bar, (as *e*.) the shaft *b'*, and wheel *b*, all operating 110 together so as to convert rotary motion into reciprocating motion, and adapted to be applied to and used in connection with a hat hardening and sizing machine, all substantially as and for the purposes herein set forth. 115

In testimony that I claim the foregoing I have hereunto set my hand this 7th day of March, 1883.

WILLIAM H. BEHRENS.
